Attest.

UNITED STATES PATENT OFFICE

JOHN STRINDLUND, OF HURUM, NORWAY

ROTARY DEWATERING SIEVE

Application filed January 3, 1930, Serial No. 418,316, and in Norway June 11, 1929.

This invention relates to dewatering sieves for cellulose and the like of the kind in which a sieve cylinder rotates partially immersed in a pulp mixture which surrounds the cylinder, 5 the pulp following the sieve out of the mixture and being removed from it at the top part of the sieve and the water leaving the cylinder through one or both ends thereof. In these known constructions the dewatering 10 is based on the difference in pressure, which is produced through the level of the outflowing water inside the sieve being lower than the level of the pulp mixture outside it. The difference in pressure is, however, greatest at 15 the lower part of the sieve and decreases as the layer of pulp approaches the level of the pulp mixture, where it becomes zero. Consequently the pulp layer tends to become detached from the sieve and has difficulty in 20 following it upwards out of the pulp mixture, adhesion only being possible on the uppermost part of the sieve.

The disadvantage is overcome by the present invention according to the main characteristic feature of which the difference in pressure referred to is maintained until the pulp layer has passed above the level of the pulp mixture, after which it may even increase.

³⁰ One constructional form of the invention is illustrated in the accompanying drawings in which

Fig. 1 is a section through a cylindrical sieve in accordance with the invention and

Fig. 2 shows diagrammatically an arrangement in which the layer of pulp is taken off the sieve by means of an endless felt cloth.

1 is a cylindrical sieve which rotates while partly immersed in a trough 2 to which the pulp mixture is conveyed by overflowing from a chamber 3. The sieve is divided at its periphery into a number of chambers or cells 4 which are covered on the outside by the sieve cloth or the covering 5. Each of the said cells communicates with one or more outflow pipes or passages 6 which are bent backwards with respect to the direction of rotation of the sieve and the length of which is such that the outflow end of the pipes does not rise out of the water in the interior of the

sieve before the cell communicating with the pipe or pipes has passed above the level of the pulp mixture and has approached the means for removing the pulp for instance the removing roller 7 with the scraper 8 shown in Fig. 1. 9 and 10 are two dandy rollers. In Fig. 2 the scraper is replaced by an endless felt cloth 11 which is guided over guide rollers 12 and a removing roller 13 and which carries the web of pulp with it and leads it away to the outside between pressing rollers 14. 55 60

When the cylindrical sieve rotates in the direction indicated by the arrow a layer will form on the sieve cloth as soon as the latter enters the pulp mixture, owing to the difference in pressure produced between the liquid level outside the drum and inside the cell. This difference in pressure increases as the sieve cloth proceeds through the pulp mixture and the water which is separated off passes into the cells and into the pipes communicating with them, filling them entirely or partially according to the water content in the pulp mixture and the volume of the cells and the pipes. When the cells and the pipes are not completely filled by the water penetrating through the sieve cloth, the remainder of the filling will take place through the outflow end

of the pipe at the moment in which the end moves below the water level in the interior of the cylinder. In view of this the cells and the pipes must be so formed that the whole of the air can escape. When such a water-filled cell and outflow pipe emerge upwards on the other side out of the pulp mixture it is necessary for the difference in pressure due to the suction to be maintained as long as the free end of the outflow pipe is below the level of the water within the cylindrical sieve, that is to say until the layer of pulp has risen out of the pulp mixture. If the layer is not too thick the air can then be drawn by suction through it. The air will however not penetrate through the layer of pulp before the latter has attained a certain degree of dryness and until this degree of dryness has been reached there will consequently be a partial vacuum in the cell which is greater than the difference in pressure between the external 100

and internal liquid level and which corresponds to the difference in height between the cell in question and the required level in the interior of the sieve. When the outflow pipe has reached a point above the water level in the interior of the cylindrical sieve any water present in the cell and in the outflow pipe will flow out causing the suction to cease and the layer of pulp will then be in a position in which it can be removed in any known manner and be conveyed as stated above to a conveying device.

As, in accordance with the present invention, the layer of pulp adheres more firmly to the cylinder so that it can be raised out of the pulp mixture in a more or less vertical position, it is possible to work with a lower level of pulp mixture so that there will be a larger portion of the sieve above it, thus increasing the time for dewatering the pulp. The upper part of the cylinder will then provide more space for several pressing members, such for instance as dandy rollers, pressing rollers or a pressing felt which are arranged and used in a known manner.

What I claim is:

1. A rotary straining device for dewatering fibrous pulp material by a difference in pressure caused by the level of the pulp mixture outside the device being higher than the level of the outflowing water on the inside of the device, comprising means for maintaining the difference in pressure until the layer of pulp adhering to the outside of the device has risen above the level of the pulp mixture outside the device, as and for the purpose set forth.

2. A rotary straining device for dewatering fibrous material by a difference in pressure caused by the level of the pulp mixture outside the device being higher than the level of the outflowing water on the inside of the device, comprising a rotary cylindrical sieve, a pervious covering for the cylindrical sieve, a plurality of cells under the said pervious covering, an outflow pipe communicating with each cell, which pipe is bent backwards in relation to the direction of rotation of the sieve and has its outflow end immersed in the water in the cylinder until the layer of pulp on the pervious covering of the cylinder has risen out of the pulp mixture outside the cylinder, as and for the purpose set forth.

3. A rotary straining device for dewatering fibrous pulp by a difference in pressure caused by the level of the pulp mixture outside the device being higher than the level of the outflowing water on the inside of the device, comprising a rotary cylindrical sieve, a pervious covering for the cylindrical sieve, a plurality of cells under the said pervious covering an outflow pipe communicating with each cell which pipe is bent backwards in relation to the direction of rotation of the sieve and having its outflow end adapted to be immersed

in the water in the cylinder while the latter rotates until the layer of pulp on the pervious covering of the cylinder has risen out of the pulp mixture outside the cylinder, said pipe being of such a length that the outflow end of the same is adapted to be immersed in the water in the cylinder some while after the layer of pulp in front of the corresponding cell has risen out of the pulp mixture, whereby the draining of the pipe and its associated cell causes air to be drawn through said layer of pulp.

In testimony whereof I have signed my name to this specification.

JOHN STRINDLUND.
